UNITED STATES PATENT OFFICE.

JOHN W. DARLEY, JR., OF BALTIMORE, MARYLAND, ASSIGNOR TO HASCAL A. HOGEL,
OF NEW YORK, N. Y.

WELL-PUMPING APPARATUS.

1,042,330.

Specification of Letters Patent. Patented Oct. 22, 1912.

Application filed December 21, 1910, Serial No. 598,536. Renewed March 19, 1912. Serial No. 634,815.

To all whom it may concern:

Be it known that I, JOHN W. DARLEY, Jr., a citizen of the United States, residing at Baltimore, in the State of Maryland, have 5 invented certain new and useful Improvements in Well-Pumping Apparatus, (Case B;) and I do hereby declare the following to be a full, clear, and exact description of the invention, such as will enable others skilled 10 in the art to which it appertains to make and use the same.

My present invention relates to apparatus for pumping out liquids from driven wells and with the use of compressed air, and is 15 more especially intended for use with wells having no great depth and where the air is forced up through and is carried off with the liquid.

My invention will be understood by reference to the accompanying drawings, in which the same parts are indicated by the same letters throughout the several views.

Figure 1 is a plan view of a well with the cap on. Fig. 2 is a side elevation of the 25 well removed from the ground, parts being broken away. Fig. 3 shows a section on the line 3—3 of Fig. 4. Fig. 4 shows a central vertical section through the well, parts being shown in elevation. Fig. 5 shows a section along the line 5—5 of Fig. 4 and looking down.

A represents a cylindrical shell forming the inner lining of the well, B' represents a perforated cone secured to the lower end 35 of said cylinder, and C represents an imperforate cone connected by spokes c and a screw-threaded sleeve c' to the air pipe E, which is screwed into the boss d in the head D, said head being screwed onto the top of 40 the cylinder A, as shown in Fig. 4. This head is provided with lugs D², D³, and D⁴, over which fit the two parts of the cap F. The cap is preferably made in two portions 45 for convenience of assembly, and the central part of the cap is provided with a bearing f for the shaft G, carrying the handle G' and the cam plate H.

The air pressure pipe I is connected to the 50 passage D⁰ in the head D, which passage opens into the top of the pipe E and also into the passage D'. The passage D⁰ is controlled by the air valve I', and the passage D' may be connected to the outer atmosphere through the passage d^s past the exhaust valve K, through the exhaust port d^o

into the chamber beneath the cap F, and may escape to the atmosphere through the opening f in said cap and through any cracks that may be in the cap itself.

The passages D⁰ and D' are cast in the 60 head D, as shown in Fig. 5. The liquid flows up into the chamber D⁰ in the base of the head D, as shown most clearly in Fig. 5, and passing into the passage d^s cast in said head, flows up into the passage d⁵ and past 65 the valve M into the chamber d⁴ in the lug D⁴, and thence to the delivery pipe L.

The three valves I, K, and M are normally pressed on their seats by springs i, k, and m, respectively. N, N', and N² are three arms 70 hinged to lugs d^s on the head D. These arms preferably carry rollers at their free ends, which rollers engage the cam plate H on one side, being pressed thereto by the valve stems of the respective valves I', K, 75 and M. The cam plate H has oppositely disposed cams h and h', the latter of which has two cam faces h² and h³.

O is a stop secured to the cover F to limit the movement of the handle G' in one direction, and the movement of the handle in the opposite direction is limited by one or the other of the arms P', P² of the bell crank lever P, which is pivoted between the lugs f². The handle G' is preferably provided 85 with a lug g, adapted to engage one or the other of the arms of the bell crank lever. These two arms are set in different planes, so that when the arm P' is vertical the handle G' is stopped at the position indicated 90 by the numeral 2. If the other arm P² be thrown in the vertical position, the handle G' may be moved over to the position indicated by the numeral 1.

The operation of the device is as follows:—The parts being in the position shown in Figs. 1, 2, and 3, the compressed air will be turned on and the chamber A will be full of air under pressure above the 95 surface of the liquid. Now if the handle G' be turned to the position indicated by the numeral 3; the air will be still kept on, but the cam face h³ will press back the arm M² and open the valve M, thus permitting 100 the compressed air to escape through the pipe L. Other compressed air rushing in through the pipe I, passage D⁰, and pipe E, will escape into the cone C, will be deflected upwardly and outwardly, and will tend 105 to blow the mass of liquid in the well A 110

vertically upward, sucking with it any liquid that may be below said cone. The mixed air and liquid will rise in the well and will continue to escape through the pipe 5 L as long as the air pressure is on and as long as the supply of liquid is maintained. In this operation, we have the buoyancy of the air, the dynamic effect by the upward rush of air, and the ejector effect caused by 10 the flow of air and liquid upward from the inner cone C, causing the liquid to be sucked upward in the annular space between said inner cone and the shell A.

When it is desired to discontinue the 15 pumping action, if the handle G' is turned to the position indicated by the numeral 1 in Fig. 1, the cam plate H will release the air valve I', which will snap to on its seat, will open the exhaust valve K, and will release the valve N, which will also snap to on 20 its seat, so that this time the interior of the well will be open to the exhaust and the air pressure will be relieved therein, permitting the liquid to seep in through the perforated 25 cone, as before. When it is desired to keep the air pressure on the well for any length of time, by keeping the arm P' of the bell crank lever P in the raised position, the handle G' cannot be turned, as by accident, 30 or carelessness, to the position for opening the exhaust.

It will be noted that the only valve whose stem requires any packing is the stem of the air valve M'.

35 It will be obvious that various modifications might be made in the herein described apparatus, which could be used without departing from the spirit of my invention.

Having thus described my invention, what 40 I claim and desire to secure by Letters Patent of the United States is:

1. A well pumping apparatus comprising an outer tube, adapted to admit liquid at its lower end, a cap normally closing the upper 45 end of said tube and provided with liquid delivery and air exhaust ports, respectively, and also with an inlet passage for compressed air, an inner tube projecting downward into said outer tube and connected at 50 its upper end to said air passage in said cap, valves normally closing said air passage and said liquid delivery and air exhaust ports, respectively, and a hand operated cam arrangement controlling said valves, substantially 55 as described.

2. A well pumping apparatus, comprising an outer tube, adapted to admit liquid at its lower end, a cap normally closing the upper end of said tube and provided with liquid 60 delivery and air exhaust ports, respectively, and also with a passage for compressed air, an inner tube projecting downward into said outer tube and connected at its upper end to said air passage in said cap, spring impressed valves normally closing said air 65

passage and said liquid delivery and air exhaust ports, respectively, and a cam plate pivoted in said cap and adapted to open either said air valve alone, or both said air and said liquid valve, or said exhaust valve 70 alone, substantially as described.

3. A well pumping apparatus comprising an outer tube, adapted to admit liquid at its lower end, a cap normally closing the upper end of said tube and provided with liquid delivery and air exhaust ports, respectively, and also with a passage for compressed air, an inner tube projecting downward into said outer tube and connected at its upper end to said air passage in said cap, spring impressed valves normally closing said air passage and said liquid delivery and air exhaust ports, respectively, and a cam plate pivoted in said cap and adapted to open either said air valve 75 alone, or both said air and said liquid valve, or said exhaust valve alone, a handle for turning said cam plate, and a bell crank lever pivoted contiguous to said handle, and having its arms in different planes, whereby said lever arms form successive stops for 80 said handle, substantially as described.

4. A well pumping apparatus, comprising an outer tube, adapted to admit liquid at its lower end, a cap normally closing the upper end of said tube and provided with liquid delivery and air exhaust ports, respectively, and also with a passage for compressed air, an inner tube projecting downward into said outer tube and connected at its upper end to said air passage in said cap, an inverted 95 cone mounted below and spaced from the lower end of said inner tube, valves normally closing said air passage and said liquid delivery and air exhaust ports, respectively, and a hand operated cam arrangement controlling said valves, substantially 100 as described.

5. A well pumping apparatus comprising an outer tube, a perforated inverted conical tip secured to the lower end of said tube, 110 and adapted to admit liquid at its lower end, a cap normally closing the upper end of said tube and provided with liquid delivery and air exhaust ports, respectively, and also with an inlet passage for compressed air, an inner tube projecting downward into said outer tube and connected at its upper end to said air passage in said cap, valves normally closing said air passage and said liquid delivery and air exhaust ports, respectively, 115 and a hand operated cam arrangement controlling said valves, substantially as described.

6. A well pumping apparatus comprising an outer tube, a perforated inverted conical tip secured to the lower end of said tube, and adapted to admit liquid at its lower end, a cap normally closing the upper end of said tube and provided with liquid delivery and air exhaust ports, respectively, and also with 120

a passage for compressed air, an inner tube projecting downward into said outer tube and connected at its upper end to said air passage in said cap, spring impressed valves 5 normally closing said air passages and said liquid delivery and air exhaust ports, respectively, and a cam plate pivoted in said cap and adapted to open either said air valve alone, or both said air and said liquid 10 valve, or said exhaust valve alone, substantially as described.

7. A well pumping apparatus comprising an outer tube, a perforated inverted conical tip secured to the lower end of said tube 15 and adapted to admit liquid at its lower end, a cap normally closing the upper end of said tube and provided with liquid delivery and air exhaust ports, respectively, and also with a passage for compressed air, an inner tube 20 projecting downward into said outer tube and connected at its upper end to said air passage in said cap, spring impressed valves normally closing said air passage and said liquid delivery and air exhaust ports, respectively, and a cam plate pivoted in said 25 cap and adapted to open either said air valve alone, or both said air and said liquid valve, or said exhaust valve alone, a handle for

turning said cam plate, and a bell crank lever pivoted contiguous to said handle, and 30 having its arms in different planes, whereby said lever arms form successive stops for said handle, substantially as described.

8. A well pumping apparatus, comprising an outer tube, a perforated inverted conical tip secured to the lower end of said tube and adapted to admit liquid at its lower end, a cap normally closing the upper end of said tube and provided with liquid delivery and air exhaust ports, respectively, and also with 40 a passage for compressed air, an inner tube projecting downward into said outer tube and connected at its upper end to said air passage in said cap, an inverted cone mounted below and spaced from the lower end of 45 said inner tube, valves normally closing said air passage and said liquid delivery and air exhaust ports, respectively, and a hand operated cam arrangement controlling said valves, substantially as described.

In testimony whereof, I affix my signature, in presence of two witnesses.
